UNITED STATES PATENT OFFICE.

SARAH A. SEYMOUR, OF TARIFFVILLE, CONNECTICUT.

READING STAND.

Application filed March 29, 1922. Serial No. 547,803.

To all whom it may concern:

Be it known that I, SARAH A. SEYMOUR, a citizen of the United States, residing at Tariffville, in the county of Hartford, State 5 of Connecticut, have invented certain new and useful Improvements in Reading Stands; and I do hereby declare the following to be a full, clear, and exact description of the invention, such as will enable others skilled 10 in the art to which it appertains to make and use the same.

This invention relates to new and useful improvements in racks and stands, and particularly to racks and stands for use by bed 15 patients.

One object of the invention is to provide a device of this character which can be used by a person who is confined to bed, for supporting a book, paper, magazine, or the 20 like, so that the person does not need to use the hands to support the article.

Another object is to provide a device of this character which is simple and durable in construction, and which can be readily 25 and easily taken down and packed in a small space, when not needed, or when the same is to be stored or shipped.

Other objects and advantages will be apparent from the following description when 30 taken in connection with the accompanying drawing.

In the drawing:

Figure 1 is an elevation of the stand.

Figure 2 is a horizontal transverse sectional view on the line 2—2 of Figure 1.

Figure 3 is an enlarged vertical sectional detail view showing the paper holding means of the stand, and the bars which support the same.

40 Referring particularly to the accompanying drawing, 10 represents a pair of standards each of which is provided with the diverging legs 11, at its lower end, and each leg being provided with a rubber covered knob 12, to prevent the legs from slipping. Telescoped on each of the standards is a tubular post 13, and engaged around each post 13, adjacent its upper end, is a collar 14, the same being adjustable along the post 45 by means of the screw 15. Also embracing the posts, adjacent their lower ends, are the similar collars 16, secured in adjusted positions along the posts by the screws 17. Each of the collars 14 and 16 is formed with 50 a laterally projecting stud 18, those of one post extending horizontally toward those of

the other post, and on these studs are engaged the opposite ends of the upper and lower angular tubes 19, it being readily seen, from the drawing, that the studs are angular. These tubes 19 fit tightly on the 60 studs, so that they will remain in adjusted positions without displacement.

Hinged to each of the tubes 19 are the fingers 20, those of the upper tube being 65 mounted at the upper edge of the tube, while those of the lower tube are mounted at the lower edge thereof. The inner face of each of the fingers is covered with felt, rubber or the like, 21, to prevent the book or paper 70 from slipping.

The paper or book is placed between the tubes 19, so that the upper edge of the paper or book lies between the upper fingers 20 and the upper tube, while the lower edge 75 of the paper or book lies between the lower fingers and the lower tube. In this manner, the paper or book is firmly held in place, the stand being placed on the bed, in front of the patient, so that he may read without 80 the necessity of holding the paper or book in his hands. It will, of course, be understood that the tubes 19 are adjusted to the height of the paper or book, so that the fingers will properly grip the upper and lower edges 85 thereof.

When the device is not in use, the tubes or posts 13 are slipped from the standards 10, and the tubes 19 slipped from the studs 18, thus permitting the device to be stored 90 in a very small space. The device may be easily and quickly reassembled when needed.

The hinges which secure the fingers 20 to the transverse tubes 19 are provided with springs 21, so that they will be strongly 95 urged toward the tubes, to firmly grip the upper and lower edges of the paper or book.

What is claimed is:

1. A reading stand comprising standards having diverging supporting feet formed 100 integral therewith, tubes telescoped on the standards, upper and lower adjustable collars clamped on the tubes and having laterally projecting studs, tubes extending transversely of the stand and having their ends 105 engaged on the studs, and pivoted spring pressed fingers on the transverse tubes for gripping engagement with the upper and lower edges of a book, or the like.

2. A reading stand comprising standards 110 having diverging supporting feet, tubes telescoped on the standards, collars clamped on

the tubes and having laterally projecting studs, tubes extending transversely of the stand and having their ends engaged on the studs, and spring pressed fingers secured to the top and bottom of the top and bottom tubes respectively and extending toward each other for overlapping engagement with the upper and lower edges of the book or the like.

- 10 3. A reading stand comprising standards having diverging supporting feet, tubes telescoped on the standards, upper and lower collars adjustably clamped on the tubes, each collar being provided with a laterally projecting stud, upper and lower tubes extending transversely of the stand and receiving the studs, and pivoted spring pressed fingers secured to the upper and lower transverse tubes and overlapping the upper and lower edges of the book respectively.
- 20 4. The combination with a pair of sup-

ports having diverging legs formed integral therewith, of a pair of tubular posts telescoping the supports, upper and lower collars clamped on the tubes and being adjustable toward and away from each other, said collars being provided with laterally projecting studs, upper and lower tubes extending transversely of the supports and having their ends engaged on the studs, spring 25 pressed fingers secured upon the upper and lower transverse tubes and extending towards each other for overlapping engagement with the upper and lower edges of the book.

30 In testimony whereof, I affix my signature, in the presence of two witnesses.

SARAH A. SEYMOUR.
